UNITED STATES PATENT OFFICE

160,572

COMBINED FLASHLIGHT AND MIRROR

Charles R. Bowland, Spring Valley, Ill.

Application April 20, 1949, Serial No. 2,163

Term of patent 14 years

(Cl. D86—10)

To all whom it may concern:

Be it known that I, Charles R. Bowland, a citizen of the United States of America and a resident of Spring Valley, in the county of Bureau and State of Illinois, have invented a certain new, original, and ornamental Design for a Combined Flashlight and Mirror, of which the following is a specification, reference being made to the accompanying drawing, forming part hereof, in which:

Fig. 1 is a top plan view of a combined flashlight and mirror, showing my new design;
Fig. 2 is a front elevational view thereof;
Fig. 3 is a side elevational view thereof; and
Fig. 4 is a bottom plan view thereof.

I claim:

The ornamental design for a combined flashlight and mirror, as shown.

CHARLES R. BOWLAND.
